(57) **CLAIM**

The ornamental design for a faucet rocket tool, as shown and described.

DESCRIPTION

FIG. 1 is a top perspective view of the faucet rocket tool, showing the new design;

FIG. 2 is a bottom perspective view of the faucet rocket tool thereof;

FIG. 3 is a front elevational view of the faucet rocket tool thereof;

FIG. 4 is a rear elevational view of the faucet rocket tool thereof;

FIG. 5 is a left side elevational view of the faucet rocket tool thereof;

FIG. 6 is a right side elevational view of the faucet rocket tool thereof;

FIG. 7 is a top plan view of the faucet rocket tool thereof; and,

FIG. 8 is a bottom plan view of the faucet rocket tool thereof.

1 Claim, 4 Drawing Sheets
